APPARATUS FOR MAKING PAPER CONTAINERS

Herbert Cross, Cynwyd, and Everett E. Bussey,
Philadelphia, Pa.Original application October 6, 1931, Serial No.
567,160. Divided and this application September
24, 1934, Serial No. 745,192

9 Claims. (Cl. 93—39)

This application is divisional with our application of Serial Number 567,160, filed October 6, 1931.

One of the objects of this invention is to provide an apparatus for the automatic manufacture of paper bottles from ribbons of paper cemented in overlapped spiral relation having the wall of the bottle securely pressed together as the same is formed.

Another object of this invention is to provide a method of making paper bottles from ribbons of paper by a sequence of steps which includes the coating of the ribbon of paper with cement just prior to its being wound upon a mandrel in overlapped spiral relation.

Another object is to provide a method of cheaply manufacturing such a paper bottle as will fulfill the above named objects, so that, if desired, such bottles can be made at the filling factory on suitable apparatus for making them automatically in quantity, as needed, and being made where the bottles are filled, the cost of much handling and transporting from the place where they are made, to the place where they are filled, is saved.

In connection with the method of manufacturing the paper bottle, it is our object to devise such a method as will lend itself to the use of paper in strip form, taken from rolls, and further, to make the bottle on a mandrel, designed to form the bottle wall of the desired shape, by winding the paper strip thereon; at the same time applying cement to the paper strips, prior to the same being wound upon the mandrel, and in a manner to be on the outside of the first formed, wound and overlapped coils of paper, while for the second layer of paper coils, applying the cement to the under side of the strip forming this second layer, to be inside the second layer coils when wound on the mandrel.

A further object in connection with our method of forming the paper bottle, as above described, is to form a plurality of overwound wrappings of strip paper at the mouth end of the bottle, and to subsequently shape the mouth and cap seat with pressure dies, adapted to shape the bottle mouth before the cement on the strip layers has had time to harden.

Inasmuch as the tapered portion of the bottle requires a shortening of one edge of the coils of paper strip, on the mandrel, in the making, it is another object of our invention to crinkle that part of the coil of paper strip, next to the edge thereof, which requires foreshortening and in a manner to form predetermined cross-fold

creases, where the foreshortening is to take place.

With these and other objects, which will hereinafter appear, our invention resides in an apparatus for making paper bottles from ribbons of paper and in the method of producing the bottles upon the apparatus, adapted for carrying out our method of making the bottle is illustrated in the drawings, and hereinafter described. Our method of forming such paper bottles, particularly upon the apparatus illustrated, is described, and what we claim in the apparatus and the method of constructing is set forth.

In the drawings,

Figure 1 is an elevation, partly broken away, 15 showing a finished form of paper milk bottle, to be made upon our apparatus.

Figure 2 is a top plan of the bottle shown in Figure 1.

Figure 3 is an elevation, partly broken away, 20 showing the bottle illustrated in Figure 1, but here in an unfinished condition, with dies shown in section, for shaping the ends.

Figure 4 is an elevation, partly broken away, 25 showing a finished form of filled paper oil bottle, with the cap cover secured in place, to be made upon our apparatus.

Figure 5 is a fragmental section of the tapered side of the mandrel upon which the bottle is to be formed, illustrating paper coils placed thereon, showing the requirement of shortening one edge of the paper coils on the tapered portion of the mandrel.

Figure 6 is a perspective view of a part of a paper strip mechanically crinkled in predetermined cross lines, along one edge thereof.

Figure 7 is a top plan of one form of apparatus adapted for making the paper bottle.

Figure 8 is a section taken on the line 8—8 of Figure 7.

Figure 9 is a perspective view of a part of the tapered portion of the mandrel, showing the manner in which the paper is crinkled and tucked to shorten one side of the paper, as it is being rolled against the mandrel.

Figure 10 is a fragmental elevation showing the hook connection of the mandrel wedge with the flanged sleeve.

In the figures, we show two of various forms of paper bottles to be made upon our apparatus. 50 One of these forms of paper bottle is the milk bottle 15, illustrated in Figures 1, 2 and 3. It has a wall 16, made up of inside and outside laminated paper strip portions. These wall portions 17 and 18 are formed independent of one another, ex- 55

cept that they are cemented together. Each of the portions 17 and 18 is formed of a plurality of overlapping and continuously wound, spiral layers of paper strip 19, wherein the strips overlap one another, so as to provide a multiple thickness of paper to each of the wall portions 17 and 18. According to the width of paper strip used and the amount of overlap for each convolution of the succeeding spiral coils of paper wound on. One can form as thick a wall portion as desired, according to the overlap and number of overlapped windings used, and have as many such wall portions as will give him the thickness of bottle wall required.

15 There is a bottom disc 20, of paper, having a flange 21, which is curled up to lock the bottle bottom both ways, to fix it therein. The mouth 22, of the bottle is formed with a cap seat 23, and a built-up flange 24, wherein several thicknesses of paper are wound together. The bottle is shown to have a cylindrical portion 25, extending from the bottom disc 20 to the point 26, where the bottle tapers convergently upward, having a reverse curve in vertical section, as 20 shown in Figure 1, and terminates in the neck 27. The tapered portion 28 extending from the point 26, to the neck 27, is made up of tucked-in spiral, overlapping strips, wherein the small, short, vertical markings 28a, on the figure, represent the multiplicity of tucks or crinkles, of the paper strip coils, forming a foreshortening of the upper strip edge, on account of the gradual reduction in the circumference of the tapered portion 28, of the bottle, as we advance toward 25 the mouth 22. A protective coating 29, of any suitable substance, as wax or lacquer, covers the bottle inside and out. The building up of such a paper bottle construction, as above detailed, is later described in connection with our method of 30 making the bottle.

40 The long oil bottle 30, is another form of paper bottle to be made upon our apparatus and is shown in Figure 4 to be similar in construction to the milk bottle, illustrated in Figure 1, except as to its top 31, and the form of the tapered portion 32, of the bottle 30.

The wall 33, of the bottle 30, has a cylindrical portion 34 and a conical portion 35, terminating in a neck 36, above which is the mouth 37. The cap 38, resting on the seat 39 is secured in place 45 by rolling in the top part 40, of the bottle wall, as at 41. The flanged portion 42, at the mouth 37, of the bottle, is made up of extra windings of paper and is formed in dies, as is the flange 24, of the milk bottle 15. While the oil bottle 30, shown in Figure 4, is first formed with an open mouth, it is here shown with the cap 38 fixed in place as it will be when filled with oil or other material, ready for the market. A protective coating 44, of suitable lacquer or other substance, covers the bottle 30, inside and out.

Considering now the apparatus illustrated fragmentally in Figures 7, 8, 9 and 10, as one kind of apparatus for carrying out the forming of the bottle from paper strips, by our method, we have shown in these figures, the relative positions of the operating elements, but have eliminated most of the framework, as well as the mechanism connected with the operating elements, for moving 70 the same.

In the apparatus shown, 45 is a long fixed bearing, in which is journaled a projecting shaft 46, fixed against end movement by the shoulder 47, on the shaft 46, and by the collar 48, pinned thereto. Any suitable connection and means for turn-

ing the shaft 46 may be provided. Upon the shaft 46, is slidably journaled the flanged collar 49, engaged by a yoke 50, pivotally fixed at 51, and having a lever arm 52, to give an end movement to the collar 49, along the shaft 46. Releasably fixed upon the end of the shaft 46, is the split mandrel 53 upon which to wind the paper strips. The mandrel 53 is shaped to correspond with the general shape of the bottle to be formed thereon, and one-half thereof is concentrically and releasably fixed upon the shaft 46. There are two mandrel halves, 54 and 55, joined elastically by screws 56, having compression springs 57, beneath their heads. Guide pins 58 serve to hold the halves 54 and 55 properly to register with one another. The screws 56 and the pins 58 pass through longitudinal slots in the long wedge 59, permitting an end movement to the wedge 59, which has a hook 60, on its large end, engaging the flanged collar 49, as shown more particularly 20 in Figure 10, for partly withdrawing the wedge 60, to collapse the mandrel halves 54 and 55, when it is desired to push off the formed paper bottle body, which is done by means of the stripping ring 61, when the rods 62, of the yoke 63, connected with the ring 61, are moved longitudinally 25 toward the small end of the mandrel 53.

30 Rollers 64 and 65 are provided for rolling the respective paper strips 66 and 67 against the mandrel 53, as these strips are being wound on 35 to form the bottle body. Each of the rollers 64 and 65, is journaled in a yoke 68, having an integral shaft 69, journaled in the bearing 70, on the end of an arm 71, which has a pivot bearing at 72, fixed on the framework. The arm 71 has 40 an extension 73 adapted for attachment to a device for holding the roller pressed against the mandrel 53, and for raising the roller from the mandrel for removal of the bottle wall formed thereon. The shaft 69 extends through the bearing 70 which has a projecting pin 74. Fixed also in the bearing 70, is a projecting pin 75. A coil spring 76 presses against the pins 75 and 77, on the shaft 69, and causes the pin 77 to press against the projecting pin 74, which is also fixed in the 45 bearing 70, tending to right the roller to normally have its axis parallel to that of the mandrel 53. Two arms 78 project upward, integral with the yoke 68. Journaled upon the arms 78, is a tucker 79, which reaches over the roller 64 50 or 65, as the case may be, and terminates in a thin wedged shaped end 80, adapted to move into the space just below the roller as a tucker-in of the bent paper strip, to form a fold. The tucker 79 has an integral upstanding arm 81, to which 55 is pivoted a link 82, adapted to be connected with some mechanism, which will operate the tucker 79, intermittently as required.

For bending the paper strip along predetermined cross lines, we provide a set of crinkling 60 toothed wheels 83 and 84, for each of the paper strips 66 and 67. The teeth of these wheels are formed to mesh together in a manner, and at that end of the wheels toward the small end of the mandrel 53, while they disappear in the circumference at the opposite end of the wheels. Each tooth has a triangular, longitudinal face, on one side, twice the depth of the face on the opposite side. The lower wheel 84 just contacts the paper strip, on the under side thereof, and is fixed with respect to the framework 85, of the apparatus which rolls upon the rails 86 and 87, being supported thereon by rollers 88. The upper wheel 83 is journaled on a pin 89, fixed in a rack bar 90, adapted to be reciprocated within the bracket 75

91, when required, by the turning of the gear 92, meshing with the rack bar 90. Suitable mechanism is to be provided for turning the gear 92, when required to lower the crinkling wheel 83, to cross-crease the paper strip between the crinkling wheels 83 and 84, when the tapered portion of the mandrel 53 is reached, to have a paper strip wound thereon.

5 Besides being crinkled, the paper strips 66 and 10 67, are each cemented on one side and are fed to the mandrel 53, between the crinkling wheels 83 and 84, by means of pairs of feed rollers 93 and 94, pressed together and mechanically turned 15 at a proper synchronized rate to feed the paper strip as required, commensurate with the winding thereof on the mandrel 53.

20 The strip 66 starts from a roll of paper 95, and passes under an idler roller 96, thence it passes over a transfer roller 97, of a liquid cement feeding device, in which 98 is the tank, in which is 25 journaled the feed roller 99, in contact with the transfer roller 97. From the roller 97, the strip 66 passes around the idler roller 100 and turns back, passing between the feed rollers 101 and 25 102, of the pair 93, from which it passes between the crinkling wheels 83 and 84, provided for the paper strip 66. The strip 66 next passes onto the mandrel 53.

30 In a similar way, the strip 67, starts from a roll of paper 103, and passes over the transfer roller 104, of a liquid cement feeding device, in which the tank 105 has journaled thereon the feed roller 106, in contact with the transfer roller 104. From the roller 104, the strip 67 passes between the 35 feed rollers 107, of the pair 94, from which it passes between the open crinkling wheels 83 and 84, provided for the paper strip 67. The strip 67 next passes on top of the first formed layer made from the strip 66.

40 All the mechanism just described for feeding, cement transferring and crinkling the paper strips, is mounted upon the framework 85, adapted to roll upon the rails 86 and 87, and moved synchronously to the related functioning elements.

45 Having described the apparatus upon which our method can be carried out, we will now proceed to describe the sequence of steps taken to produce a paper bottle thereon.

50 Assume that the mandrel 53 is of the required shape for forming the bottle thereon, and that the rolls of paper strips and cementing devices are in place, we start to wind the strip 66, on the mandrel 53, beginning at the stripping ring 55 61, having first threaded the strip 66 from the roll 95, under the roll 96, over the transfer roll 97, around the roll 100 between the feed rollers 101 and 102 and between the open crinkling wheels 83 and 84, and onto the mandrel 53, having releasable means for attaching the beginning end of the strip 66. The mandrel is then rotated, winding on the first coil of the strip 66, and at the same time, the framework 85 is mechanically moved forward, at a rate to produce the desired 60 overlap of the second and succeeding coils, until the length of wall portion made up of the first formed layers of overlapped paper, reaches a distance commensurate with the spaced relation of the rollers 64 and 65, at which time, the strip 67 is attached next to the stripping ring 61. As the coils of the strip 66 are wound on, the roller 64 is pressed against them to consolidate the overlapping coils, which have previous to coming onto the mandrel, been cemented on the upper side, by

the cement transfer roller 97, and fed along by the mechanical turning of the rolls 101 and 102, the speed of which is regulated, to the rate of winding of the coils upon the mandrel, which speed varies according to the diameter of the 5 portion of the mandrel wound upon, being greater for the cylindrical portion, and less and less, in gradual reduction, as the coils are wound upon the tapered portion of the mandrel toward the mouth. After the forming of the first wound 10 layers of the paper strip 66 has reached a distance commensurate with spacing of the rollers 64 and 65, then the end of the other paper strip 67, is started by being cemented onto the first formed part of the inner wall portion of the 15 bottle wall, next to the stripping ring 61, as the mandrel continues to rotate.

20 After the strip 67 is started on the mandrel and is coursing from the roll 103, cemented at roller 104, fed by the pair of rollers 94 and passing through the open crinkling wheels 83 and 84, the spiral winding of both the strips 66 and 67, continues, and as they successively reach the point on the mandrel, where the tapering begins, as indicated by the broken lines 108, the 25 crinkling wheels 83 and 84, in each case, are brought together to crease the paper along the edge 109. 110 represents the position of the crinkling wheels 83 and 84, at the beginning of the taper. As each strip, so crinkled, as at 111, reaches the tapered portion of the mandrel, beneath the roller 64 or 65, as the case may be, the tucker 79 is started to reciprocate and tuck the paper in at the creases to form folds, having the narrow triangular creased portion 112, 30 overlap the wider triangular creased portion 113, of the strip as shown at 114 on Figure 7, and particularly illustrated at 115 on Figure 9. The rolling on of both strips, 66 and 67, continues in succession until the desired length of 40 the inner wall portion of the bottle is reached, when the strip 66 is cut through and the pair of feed rollers 93 is stopped, but before the end of the inner wall portion has been completed, the crinkling wheels are separated and stopped 45 at the neck just below where the mouth flange is to be formed. However, the carriage having the framework 85, continues to advance for the continued winding on of the strip 67, up to, and a little beyond the finished inner bottle wall 50 portion, when the carriage is stopped and the winding continues to build up the body of the flange portion of the bottle after which, the pair 94 of the feed rollers is stopped and the strip 67 is cut off.

55 During the winding on of the strip 67, and the crinkling thereof, the crinkling rollers 83 and 84 provided for use of the strip 67, are also stopped and spread apart, as the end of the tapered portion of the mandrel is reached at 60 the neck as was done in connection with strip 66.

After the bottle wall, with its two wall portions is formed, and is cut loose from both strips 66 and 67, and the mandrel 53 stopped, the wedge 59 is withdrawn sufficiently by the flanged sleeve 65 49, to cause the springs 57 to draw the mandrel halves 54 and 55 closer together, in a manner collapsing the mandrel in size sufficiently to loosen the bottle wall therefrom, when the stripping ring 61 is moved forward, stripping off the 70 bottle wall so formed, which is next positioned to receive the flanged bottle bottom. This flanged bottom as 20, in Figure 1, is pushed up into the lower end of the bottle wall, after which, and before the cement has hardened be-

tween the layers of paper strips forming the bottle, the bottle wall with its bottom in place is positioned relative to the split die 116, at the neck of the bottle, and the seat and flange forming die 117, as shown in Figure 3. These dies 116 and 117 are forced together to form the finished top of the bottle, and either the die 118, or a suitable rolling means is used to form the curling in of the flange 21 and the skirt 119, of the lower end of the bottle to have the flange 21 of the bottom 20, interwound in coiled up relation to the bottle skirt 119, to lock the bottom both ways on the bottle wall.

The bottle thus formed, is next dried out and the cement permitted to harden, after which, the bottle is coated inside and out with wax or lacquer, as desired, and is dried when it is a finished milk bottle with a cap seat 23, ready to receive milk and be capped by the usual glass bottle cap of cardboard.

In the case of forming on a different shaped mandrel, the oil bottle, illustrated in Figure 4, the wall and bottom thereof, is formed in a way similar to that described in connection with the forming of the milk bottle, except that the outer wall portion of the oil bottle is wound beyond the end of the inner wall portion, sufficiently to afford enough stock to roll in on top of the cap, put in place after filling the bottle with oil. After the oil bottle wall is formed, with the bottom fixed in place, as described for the milk bottle, the cap seat is squared off by proper dies before the cement hardens and after being thoroughly dried, the bottle is coated inside and out with a suitable wax or lacquer and is made ready for filling. After filling the bottle with oil or other substance, which the bottle is to carry, the cap is put in place and the top of the bottle wall is rolled or curl-pressed in, on top of the cap to securely seal the bottle.

By using other forms of mandrels, either circular or oblong, in cross-section, which can be collapsed, permitting the bottle wall formed thereon to be stripped off, other shapes of bottles can be formed, than the two kinds of bottles herein illustrated.

Inasmuch as other changes can be made in the apparatus, as well as changes in the steps or sequence of steps, in our method of forming the bottle, without departing from the spirit and scope of our invention, we wish to include all modifications of the apparatus and method which come within the purview of the following claims.

We claim:

1. An apparatus for automatically making paper bottles from ribbons of paper which includes in combination a collapsible mandrel of the shape of the bottle to be made, means for holding a roll of paper ribbon from which the paper is fed upon the mandrel, means for applying cement to the surface of the paper ribbon, means for turning the mandrel, means for gradually moving the paper holding means longitudinally of said mandrel, and other means for compressing a thickened mouth to said bottle into a desired shape.

2. An apparatus for automatically making paper bottles from ribbons of paper which includes in combination a collapsible mandrel of the shape of the bottle to be made, means for holding a roll of paper ribbon from which the paper is fed upon the mandrel, means for applying cement to the surface of the paper ribbon, means for turning the mandrel, means for grad-

ually moving the paper holding means longitudinally of said mandrel, and means for tucking one edge of said ribbon as the same is being wound upon said mandrel.

3. The method of forming paper bottles from paper strip, consisting of winding said strip in spiral, overlapping coils upon a mandrel, to form the bottle wall, cementing said strip on one side thereof before winding the same on said mandrel, forming extra winds on said wall to build up a flange thereon, compressing said flange longitudinally of the axis of the said bottle into the desired shape, and inserting a bottom disc in said bottle wall.

4. The method of forming paper bottles from paper strip consisting of winding said strip in spiral, overlapping coils upon a mandrel to form a wall portion layer to the bottle, cementing said strip on the outside thereof, before winding the same on said mandrel, winding another strip in spiral overlapping coils upon said mandrel on top of said first formed wall portion layer, to form a second wall portion layer, cementing said other strip on its inside before winding upon said first formed wall portion and forming a bottom in said bottle wall.

5. The method of forming paper bottles from paper strip consisting of winding said strip in spiral, overlapping coils upon a mandrel to form a wall portion layer to the bottle, cementing said strip on the outside thereof, before winding the same on said mandrel, winding another strip in spiral overlapping coils upon said mandrel on top of said first formed wall portion layer, to form a second wall portion layer, cementing said other strip on its inside before winding upon said first formed wall portion, the forming of extra windings of said second strip on a portion of said second wall portion layer to form a flange thereon, and die pressing said flange to form the same into the desired shape, then forming a bottom in said bottle wall.

6. The method of forming paper bottles from paper strip consisting of winding said strip in spiral, overlapping coils upon a mandrel to form a wall portion layer to the bottle, cementing said strip on the outside thereof, before winding the same on said mandrel, winding another strip in spiral overlapping coils upon said mandrel on top of said first formed wall portion layer, to form a second wall portion layer, cementing said other strip on its inside before winding upon said first formed wall portion, the forming of extra windings of said second strip on a portion of said second wall portion layer to form a flange thereon, and die pressing said flange to form the same into the desired shape, and die pressing a cap seat in the mouth of said bottle wall, then forming a bottom in said bottle wall.

7. The method of forming a paper bottle from coils of paper strip, wherein said bottle has a tapered portion to the wall thereof, including the winding of said strip in spiral, overlapping coils upon a mandrel, to form a wall to said bottle, cementing said strip on a side thereof before winding the same on said mandrel, and foreshortening one edge of the coils forming said tapered portion of said wall, by crinkling said strip at said foreshortened edge, forming the crinkling by cross creasing said strip prior to winding and tucking the same at said creasings automatically, beneath a pressure roller, forming a series of cross folds which foreshorten one edge of the paper strip, as it comes into the winding operation.

8. A method of forming a paper bottle, whereby strips of paper are overlappingly wound upon a mandrel of the shape desired for the bottle, of applying cement to the outside of the first layer of strip paper wound on the said mandrel, of applying another layer of paper strips wound over the first layer to be wound on the mandrel, of cementing the last named layer of paper, by applying the cement to the inside of the strip as the latter is entering the act of winding, of distorting end overlapping layers of paper, by pressure dies forming a mouth portion of the desired shape, and of coating the inside of the bottle so formed, with a sanitary and protective liquid coating.

5
10
15

9. An apparatus for automatically making paper bottles from ribbons of paper, having in combination with a frame, a mandrel shaft journaled upon said frame, a split mandrel mounted upon said shaft, said mandrel comprising two half forms, pin members fixed in one of said forms in sliding engagement with holes in the other of said forms, spring means on one of said forms, tending to normally urge said mandrel forms together, a longitudinal wedge member between said forms, for releasably holding said forms spaced apart, means for partially withdrawing said wedge member to lessen the peripheral size of said mandrel, means supporting a roll of paper ribbon on said frame and means for guiding said ribbon as it is wound upon said mandrel.
